UNITED STATES PATENT OFFICE.

ERNEST H. BAXTER, OF CHICAGO, ILLINOIS.

REFILLABLE FUSE PLUG.

1,407,117.

Specification of Letters Patent. Patented Feb. 21, 1922.

Application filed October 27, 1919. Serial No. 333,749.

To all whom it may concern:

Be it known that I, ERNEST H. BAXTER, a citizen of the United States, residing at Chicago, in the county of Cook and State of Illinois, have invented a certain new and useful Improvement in Refillable Fuse Plugs, of which the following is a full, clear, concise, and exact description, reference being had to the accompanying drawings, 10 forming a part of this specification.

My invention relates to fuse plugs and more particularly to a fuse plug in which the fuse element may be renewed after being burned out.

15 In most of the lighting circuits in use at the present day and in many of the smaller electric circuits fuse plugs are used which have the general form of the screw plug on the ordinary electric lamp bulb. These plugs 20 are screwed into a socket having electrical connections like those of an ordinary lamp socket. The fuse contained within the plug is adapted to conduct a certain amount of current without melting. If the current exceeds the amount for which the fuse is intended the fuse burns out and a new plug must be inserted. The fuse itself forms only a small portion of the fuse plug but the entire plug must, at the present time, be thrown 25 away because the plug is not so constructed that an amateur or a person unskilled in the electrical art can reinsert a new fuse. Throwing away the entire plug when only the fuse is destroyed entails a great loss. It is an object of this invention to avoid this loss by providing a fuse plug having means whereby a new fuse may be inserted by any person not skilled in the art and without the use of any but ordinary implements. It is a further object of the invention to provide a fuse plug of the character set forth which is inexpensive to manufacture, servicable in use and is fire-proof as is necessary in plugs of this kind.

45 It is a further object of the invention to provide a fuse plug in which the usual glass or isinglass cover plate may be removed so that access may be had to the interior of the plug for re-inserting a new fuse.

50 With these and other objects in view which will be apparent from the detailed description which follows I have disclosed in the drawings two forms which my invention may take, which forms are the best known to me at the present time. However, it is to be understood that by this specification and

the accompanying drawings I do not intend to limit myself to the specific construction disclosed but intend to avail myself of any modifications which fall within the claims 60 appended to this specification.

In the drawings the same reference characters have been used to designate the same parts throughout the several views. In these drawings—

65 Fig. 1 is a central section taken on line 1—1 of Fig. 3 through the preferred form of my improved fuse plug;

Fig. 2 is a fragmentary sectional view showing a slightly modified means for attaching the free end of the fuse;

Fig. 3 is an end view of the plug, viewing it from the contact end;

Fig. 4 is a perspective view of the fuse holding element;

Fig. 5 is a perspective view of the renewable fuse.

In the drawings the reference character 10 designates the porcelain body portion of the plug. The body is provided with exterior 80 threads 11, the purpose of which will be set forth later. The body is enlarged above the threads 11 as shown at 12 in Fig. 1 and this enlarged portion has exterior threads 13 which are adapted to be engaged by a threaded cover member 14. This cover member has a circular opening 15 in its top and is adapted to hold a piece of glass or isinglass 16 against the end of the body in order to close this end of the body. The body 10 has a hollow interior as shown in Fig. 1 and when it is desired to gain access to the interior of the body it is only necessary to unscrew the cover member 14 and remove it together with the glass 16.

95 The other end of the body 10 is provided with the circular opening 17 which is adapted to receive a collar 18 having a threaded interior. The collar 18 is conveniently held in place in the body 10 by having its ends 100 bent outwardly around the body member as shown in Fig. 1 of the drawings.

One side of the body member is provided with an opening 19 and positioned within this opening is the clamping portion of a 105 fuse holding element 20. The lower portion 21 of the fuse holding element is shaped or corrugated as shown in Figs 1 and 4 so that it may fit over the threads 11 of the body member 10. The upper portion of the fuse holding element which I termed the clamping portion and which is designated by the nu-

meral 22 is bent substantially into the shape of a W and has a holding portion 22^a as will be clear from Fig. 4 of the drawings. The free end of the fuse holding element projects laterally and forms a finger piece 23 which is positioned adjacent the enlarged portion 12 of the body 10 as will be clear from Fig. 1.

Encircling the body member 10 is a threaded ring-like member 24 which encircles the threads 11 on the body member 10 and whose exterior threads are adapted to engage the threads of the socket in which the plug is used. The parts are assembled by first positioning the clamping portion 22 in the opening 19 and the portion 21 over the threads 11 of the body member. The member 24 is then screwed onto the body member until the shoulder 25 formed thereon engages the shoulder 26 formed on the body member 10. The member 24 fits the body 10 with a tight fit so that additional holding means are not necessary in order to retain the parts in the desired relation.

The parts above described constitute the permanent portion of my improved plug. It is intended that the purchaser shall be compelled to buy the plug portions described above, only once and, thereafter when the plug burns out a new fuse will be inserted which fuse will now be described.

The fuse comprises a screw-like member 27 which is provided with a slotted head 28 upon which may be impressed the numeral designating the amount of current for which the fuse is adapted. The screw 27 is split as shown at 29 and is adapted to receive between the prongs so formed one end of the fuse 30. The end which I designate 31 is made slightly wider than the fuse 30 so that it may be more readily secured within the slot 29. This securing may be effected by making the slot 29 slightly narrower than the thickness of the end 31 and forcing the end 31 into the slot or the ends of the screw 27 may be bent into firm contact with the end 31 after it is inserted in the slot.

The other end 32 of the fuse is also enlarged and is adapted to be held by the clamping portion 22 of the fuse holding element. By pressing down on the finger piece 23 by means of the finger or any suitable instrument the ends 33 of the clamping portion are spread apart so that the fuse may be inserted between them. When the finger is released the ends 33 will spring toward each other and firmly hold the end of the fuse between them.

In Fig. 2 I have shown a slightly modified means for holding the end of the fuse in position. The body member 10^a is provided with exterior threads 11^a which are engaged by the threaded ring-like member 24 as in the previous modification. The holding element 20^a has its upper end bent inwardly through an opening 34 provided in the body

member 10^a and this bent over portion 35 is provided with a threaded opening as shown in Fig. 2. Above the portion 35 is a clamping plate 36 having a suitable opening which is adapted to receive a screw 37 which engages the threaded opening in the portion 35. After the end 32 of a fuse has been inserted between the clamping member 36 and the portion 35 the screw 37 is tightened and this serves to securely hold the end of the fuse in position. The cover 14 and the glass 16 are the same as for the modification first described.

While I have described the body members 10 and 10^a as made of porcelain I do not intend to limit myself to the use of this specific material but intend to avail myself of all materials having the required insulating properties. The cover 14, the ring-like member 24 and the collar 18 are preferably made of the usual brass material but other materials may be used. The fuse holding elements 20 and 20^a are preferably made of zinc but any conducting material which is resilient enough to afford the clamping action of the ends 23 may be used instead. Also while I have shown the fuse 30 formed with a narrower body portion and enlarged ends, this construction is merely a convenient one and is not the only one which may be used with the plug described. The invention does not reside in any selection of materials but consists of a fuse plug wherein the fuse may be readily renewed by persons not skilled in the electrical art.

Having thus described my invention what I claim as new and desire to secure by United States Letters Patent is:

1. A fuse plug of the character set forth comprising a body member, a removable cover therefor, a fuse holding element carried by the body member and detachably clamped to the side thereof, and a fuse adapted to be freely inserted into said holding element.

2. A fuse plug of the character set forth, comprising a body member having an opening in one end thereof and a second opening in the side wall thereof, a readily removable fuse secured in said end opening, and clamping means in the opening in the side wall of said body member for detachably securing the other end of said fuse in said opening.

3. A renewable fuse plug comprising a body member, a removable cover therefor, an opening in one end of the body member, a fuse detachably held in said opening, and a fuse holding element carried by and projecting through an opening in said member and adapted to detachably hold one end of said fuse in said latter opening.

4. A fuse plug of the character described comprising a body member having an opening therethrough, a fuse holding element for readily detachably holding a fuse having a

clamping portion projecting through said opening, an opening in the end of said body member and a fuse detachably held in said end opening and having its free end detachably secured to said holding element.

5. A renewable fuse plug of the character described comprising a body member having an exteriorly threaded portion and an opening in one of its sides, a fuse holding element projecting through said opening and over-lying the threads on said body member, and a ring-like member having threads adapted to engage the threads of said body member to clamp said fuse holding element against the body member.

6. A renewable fuse plug comprising a body member having an exteriorly threaded portion and an opening in one of its sides, a fuse holding element for readily detachably holding a fuse projecting through said opening and overlying the threads on said body member, a threaded ring-like member engaging the threads of said body member and clamping said fuse holding element against the body member, a threaded collar secured in one end of said body member, and a fuse member carrying a screw portion adapted to engage said threaded collar, said fuse member having its free end detachably secured to said fuse holding element.

7. A fuse holding element for a renewable fuse plug of the character set forth comprising a corrugated portion and a clamping portion, said clamping portion being provided with a finger piece and clamping ends, the parts being so constructed that when said finger piece is moved said ends will be separated to receive a fuse between them.

8. A renewable fuse plug comprising a body member having an opening in one of its ends, a ring of conducting material surrounding said body member, a fuse holding element electrically connected to said ring and having a clamping portion projecting through an opening in said body member, and a fuse adapted to be detachably secured in said first named opening and to have its free end detachably secured to said holding element.

9. A fuse plug of the character set forth, comprising a body member having an opening in one end thereof and a second opening in the side wall thereof, a readily removable fuse having a screw threaded member on one end thereof adapted to be secured in said end opening, and clamping means for detachably securing the other end of said fuse in the opening in the side wall of said body member.

10. A fuse plug of the character set forth, comprising a body member having an opening in one end thereof and a second opening in the side wall thereof, a readily removable fuse having a screw threaded member on one end thereof adapted to be secured in said end opening, and clamping means for detachably securing the other end of said fuse in the opening in the side wall of said body member, said clamping means having an angular portion about which said fuse may be bent.

In witness whereof, I hereunto subscribe my name this 23rd day of October, A. D. 1919.

ERNEST H. BAXTER.
